(57) **CLAIM**

The ornamental design for a cup, as shown and described.

DESCRIPTION

FIG. 1 is a perspective view of a cup with a lid illustrated in broken line;

FIG. 2 is a side view of the cup;

FIG. 3 is a top view of the cup; and,

FIG. 4 is a bottom view of the cup.

The broken lines in FIG. 1 represent environmental structure and form no part of the claimed design.
